UNITED STATES PATENT OFFICE

94,689

DESIGN FOR A BURNER, BOWL, AND UTEN- SIL SUPPORT ASSEMBLY FOR A COOK STOVE

Stanley H. Hobson, Rockford, Ill., assignor to
Geo. D. Roper Corporation, Rockford, Ill., a
corporation of Illinois

Application April 20, 1934, Serial No. 51,467

Term of patent 7 years

To all whom it may concern:

Be it known that I, Stanley H. Hobson, a citizen of the United States, residing at Rockford, in the county of Winnebago, and State of Illinois, have invented a new, original, and ornamental Design for a Burner, Bowl, and Utensil Support Assembly for a Cook Stove, of which the following is a specification, reference being had to the accompanying drawing, forming part thereof.

In the drawing:

Figure 1 is a perspective of a burner, bowl,

and utensil support assembly for a cook stove showing my new design;

Fig. 2 is a plan view of said assembly;

Fig. 3 is a side view, and

Fig. 4 is a section of the bowl on the line 4—4 of Fig. 2 to better illustrate the shape thereof.

I claim:

The ornamental design for a burner, bowl, and utensil support assembly for a cook stove, substantially as shown and described.

STANLEY H. HOBSON.
